[57] CLAIM

The ornamental design for an eyewear lens, as shown and described.

DESCRIPTION

FIG. 1 is a top plan view of an eyewear lens showing a first embodiment of our new design;

FIG. 2 is a front elevation view thereof;

FIG. 3 is a right side elevational view thereof, the left side being a mirror image;
FIG. 4 is a bottom plan view thereof; and,
FIG. 5 is a rear elevational view thereof;
FIG. 6 is a perspective view of an eyewear lens showing a second embodiment of our new design;
FIG. 7 is a top plan view thereof;
FIG. 8 is a front elevation view thereof;
FIG. 9 is a right side elevation view thereof, the left side being a mirror image;
FIG. 10 is a bottom plan view thereof; and,
FIG. 11 is a rear elevation view thereof;
FIG. 12 is a perspective view of an eyewear lens showing a third embodiment of our new design;
FIG. 13 is a top plan view thereof;

FIG. 14 is a front elevational view thereof;
FIG. 15 is a right side elevation view thereof, the left side being a mirror image;
FIG. 16 is a bottom plan view thereof; and,
FIG. 17 is a rear elevation view thereof;
FIG. 18 is a perspective view of an eyewear lens showing a fourth embodiment of our new design;
FIG. 19 is a top plan view thereof;
FIG. 20 is a front elevation view thereof;
FIG. 21 is a right side elevation view thereof, the left side being a mirror image;
FIG. 22 is a bottom plan view thereof; and,
FIG. 23 is a rear elevation view thereof.
